UNITED STATES PATENT OFFICE

GEORGE F. GEHRI, OF TACOMA, WASHINGTON

AIR WASHER FOR FURNACES

Application filed January 29, 1930. Serial No. 424,272.

This invention relates to devices for cleaning and humidifying the air about to be heated by a domestic furnace. The objects of my invention are, first, to provide an air washer which will effectively clean and charge the air with moisture; second, which will eliminate the annoying sound of dripping water within the washer; third, which will prevent leakage at the joint thereof with the furnace boot; fourth, which may be readily inspected; and fifth, which is cheap to make and to operate.

I attain these and other objects by the devices and arrangements illustrated in the accompanying drawing, in which:—

Fig. 1 is a perspective view of my improved air washer, showing it in relation to the air-supply fan and to the furnace; Fig. 2 is a vertical section thereof. Similar numerals of reference refer to similar parts throughout the several views.

My improved air-washer is adapted to be interposed immediately between the air supply fan, mounted in the fan casing 1, and the boot 2 of the furnace 3. It comprises a main receptacle or box 4, of metal, having an open top on which a removable cover or lid 5 is fitted, together with an inlet passage 6, and an outlet passage 7 which contains the eliminator 8.

The very fine spray, or fog, or mist, of water which is projected into the box 4 by the nozzles, fills the said box and collects on the lid 5 and on the side walls of the box in the form of drops. These drops are too large to be readily absorbed by the air and would pass freely through the air stream if they were not collected and conducted down to the base of the box. Such drops would thus produce an annoying and constant drip in the box which it is one of the principal objects of this invention to eliminate.

The four vertical walls of the main box 4 are folded inward at the upper end to form a trough 9, as shown, extending entirely around the box opening. The lid 5 is provided with a vertical flange 10, extending downward into said trough 9. The width of the trough 9 is such that its inner walls extend inward from the flange 10. The lid 5 may preferably be

made of corrugated metal in order to gather the moisture falling thereon and carry it to its sides or edges and thus to the trough 9. A series of holes 11 may be made in the bottom of the trough 9 to permit the escape of the water collected therein. A small lip or cup 12 is fastened to the inside of the walls of the box 4, under each of the outlet holes 11, and is adapted to catch the drip from said holes and to conduct it to the sides of the box, where it escapes through a hole 13 in the cup 12. Thus all the water which reaches the lid 5 is led to the inner sides of the walls of the box 4 and causes no dripping or splashing noise.

The connection between the inlet passage 6 and the main box 4 is also protected from drip by a trough 14 which surrounds its three sides and which leads all water, which finds its way thereto, down the sides thereof to the bottom of the box 4.

A flange 15 similarly surrounds three sides of the connection between the box 4 and the outlet passage 7. This flange 15 also forms the back stop for the eliminator 8 which is positioned just outside of the said flange 15.

The eliminator 8 is of the usual construction and consists of a series of parallel bent plates between which the stream of wet air passes and which collect the free moisture therefrom as it passes from the washer to the furnace 3.

An inclined apron 16 is secured to the outer end of the lower inclined side of the outlet passage 7 and catches any moisture from the eliminator 8 which might try to escape to the joint 17 between the outlet passage 7 and the furnace boot 2, leading such water back into the box 4, thus enabling the said joint to be made in the usual way without risk of leakage of water therethrough. A flange 18 forms a part of this joint 17 and holds the outer side of the eliminator 8. The said eliminator 8 is mounted on a stand 19, having holes 20 in its bottom edge to permit the return of water from the eliminator 8 back to the box 4 by way of the inclined bottom of the outlet passage 7 and under the said stand 19.

The water for the air-washer is supplied

by a pipe 21, which enters the box through one side thereof and which is provided with several spray nozzles adapted to throw a fine mist of water into the box. The air is driven by the fan in the fan casing 1, through the inlet passage, into and through the main box 4, where it passes through the said mist or spray of water and is thoroughly cleaned of any dust and noxious gases and also absorbs a portion of the free moisture therein; 10 the wet air then passes through the eliminator 8 where all free and surplus moisture is removed, and thus through the passage 7 and boot 2 to the air-heating chamber of the furnace 3.

15 The water from the pipe 21, which is not absorbed by the air or caught by the eliminator, reaches the lid 5 or the walls of the box and is conducted down to the bottom of the box without any dripping noise. A 20 waste pipe 22 removes the water and the dirt from the washer.

25 The bottom surfaces of both the inlet passage 6 and the outlet passage 7 are inclined downward towards the box 4 to keep all water away from the joints at the ends of the said passages. The lid 5 is made with sloping sides to cause the water thereon to run to the trough 9.

30 Having described my invention, what I claim is:—

35 1. An air-washer for furnaces, comprising a main box with means for creating a liquid spray therein and having an open top; an in-turned trough formed around the said open top; a lid having sloping sides and a vertical peripheral flange resting in said trough; and drainage holes in said trough, adapted to conduct the water from the lid to the side walls of the box.

40 2. An air-washer for furnaces, comprising a main box with means for creating a liquid spray therein and having an open top; an in-turned trough formed around the said open top; a lid of corrugated material, and having sloping sides and a vertical peripheral flange resting in said trough; and drainage holes in said trough, adapted to conduct the water from the lid to the side walls of the box.

45 3. An air-washer for furnaces, comprising a main box with means for creating a liquid spray therein and having an open top; an in-turned trough formed around the said open top; a lid having sloping sides and a vertical peripheral flange resting in said trough; drainage holes in said trough; and cups, having an opening adjacent the wall, and secured to the wall of said box below each such drainage hole, whereby the water from the 50 lid is conducted to the walls of the box.

55 4. An air-washer for furnaces, comprising a main box with means for creating a liquid spray therein and having an open top; an in-turned trough formed around the said open top; a lid of corrugated material, and having

sloping sides and a vertical peripheral flange resting in said trough; drainage holes in said trough; and cups, having an opening adjacent the wall, and secured to the wall of said box below each such drainage hole, whereby the water from the lid is conducted to the 70 walls of the box.

5. In an air-washer for furnaces having a main mist-holding box with vertical walls and with means for creating a water mist therein, and a horizontal dry-air inlet passage opening into said mist-holding box through one said vertical walls; with a trough within said mist-holding box and partially surrounding the said opening in its vertical wall and adapted to prevent the dripping of water across the stream of dry air passing through said opening and to collect the drops from the wall and to conduct them from the vertical wall to a point below said opening.

6. In an air-washer for furnaces having a main spray box having an outlet opening therein; a furnace boot; an air passage having a bottom inclined downward towards the box and positioned between the box and the boot; a stand on said inclined bottom, adapted to permit water to pass thereunder down said incline but to prevent air from passing out thereunder from said box; and an eliminator mounted on said stand and adapted to 95 permit the air to pass therethrough from said box to said boot and to collect the free water from said air.

7. In an air-washer for furnaces having a main spray box having an outlet opening 100 therein; a furnace boot; an air passage having a bottom inclined downward towards the box and positioned between the box and the boot; a stand on said inclined bottom, adapted to permit water to pass thereunder down said incline but to prevent air from passing out thereunder from said box; an eliminator mounted on said stand and adapted to permit the air to pass therethrough from said box to said boot and to collect the free water 110 from said air; and an inclined apron positioned in said passage beyond said eliminator and extending above the level of said stand and adapted to receive the drops of water blown from the base of said eliminator and 115 to return them by the inclined bottom of the passage to the box and thereby prevent their entrance into said boot.
